CLAIM

The ornamental design for a scoop holder, as shown and described.

DESCRIPTION

FIG. 1 is a top perspective view of a scoop holder;
FIG. 2 is a bottom perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof;
FIG. 9 is another bottom perspective view thereof; and,
FIG. 10 is another bottom perspective view thereof.
The broken lines show environmental subject matter and form no part of the claimed design.
